UNITED STATES PATENT OFFICE.

ARTHUR E. SNOW, OF ERIE, PENNSYLVANIA, ASSIGNOR TO THE AMERICAN LAUNDRY MACHINERY COMPANY, OF NORWOOD, OHIO, A CORPORATION OF OHIO.

CLOTHES-PRESSING APPARATUS.

1,309,589.

Specification of Letters Patent.

Patented July 8, 1919.

Application filed January 29, 1918. Serial No. 214,304.

To all whom it may concern:

Be it known that I, ARTHUR E. SNOW, a citizen of the United States, residing at Erie, in the county of Erie and State of Pennsylvania, have invented certain new and useful Improvements in Clothes-Pressing Apparatus; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to clothes-pressing apparatus and consists of the improvements hereinafter pointed out.

The features of my invention are herein-after described and are illustrated in the 20 accompanying drawings, in which:—

Figure 1, is a side view of a clothes pressing apparatus with a portion broken away, embodying my invention.

Fig. 2, is a plan view thereof.
25 Fig. 3, is an enlarged transverse section of the buck B'.

In these drawings A indicates a hollow pedestal having ears A' A' at the upper end thereof, the body of said pedestal being 30 preferably channel shaped as shown in the drawings. Upon the front face thereof is a bracket B which supports a buck B', which is hollow to receive steam from the pipe B², by which the same is heated in the 35 usual manner. The buck B' is provided with an upper plate b which is provided with perforations b', and a chamber b² under said perforated plate, to which steam may be supplied when desired, through the pipe 40 C, as hereinafter described, for the purpose of steaming the goods being pressed.

Under the chamber b² in the buck B' is another chamber b³ to which steam is continuously supplied by means of the pipe B² 45 for the purpose of heating the buck B'; the supply of steam to the chamber b³ being continuous, while the supply of steam to the chamber b² is occasional.

Pivoted to the ears A' A' by means of the 50 pivot α is an oscillating, bifurcated beam D to one end of which is secured a presser-head D' adapted to be pressed down upon the heated buck B', and on the other end of said beam D is a counter-weight D², to 55 balance the board D', all of which parts are

old and well known in the art, and form no part of the present invention, the present invention relating particularly to the control of the valve by means of which steam is admitted to the pipe C.

60 In the pipe C is an ordinary spring pressed valve E having a valve-stem e, an operating lever E' to which I pivot a bar F which extends to a bell-crank lever F' which is pivoted to the pedestal A, one arm 65 thereof extending through a slot in the front of said pedestal as shown in Fig. 1, upon which arm a weight F² is suspended to normally maintain said lever F', bar F and valve lever E' in the position shown by full 70 lines in Fig. 1.

Mounted upon the pivot α between the arms of the bifurcated beam D is a grooved pulley wheel G. The bifurcated arms of the beam D are provided with extensions 75 d d which project beyond the front edge of the presser head D', and between the ends of these extensions is pivoted a hand bar or roller d', which is adapted to be grasped by the hand of the operator when it is desired to raise or lower the presser head D' as shown by broken lines in Fig. 1. Upon the roller d' is secured an arm H, and from the arm H a cord, chain or cable H' extends over the grooved wheel G to an arm 80 of the bell-crank lever F', so that by causing the roller d' to rock, the arm H is oscillated, as shown by broken lines in Fig. 1, and the cord or chain H' lifts the weighted arm of the lever F', which through the bar F operates the valve lever E' as indicated by broken lines in Fig. 1 and operates the valve-stem e so that without taking the hand from the roller d' the valve E may be opened to admit steam to the pipe C. The mechanism 85 for operating the valve E thus shown and described, is very simple, but it is obvious that the valve E may be operated by the hand which raises or lowers the presser-plate D in many other forms of mechanism 90 not herein shown and described, without departing from the scope of my invention; therefore I do not desire to be limited to the exact construction and arrangement of mechanism hereinbefore shown and described but what I claim and desire to secure is:—

1. In a clothes pressing apparatus, an upright column forming the frame, a stationary buck secured to a bracket on said column, 110

a pipe for supplying steam to said buck, a valve for controlling the steam passing therethrough to said buck, a centrally pivoted arm mounted on the top of said column, 5 a presser-plate on said arm adapted to be brought into contact with the top of said buck, a handle on said lever for operating it, a counter-weight on the opposite end of said centrally pivoted arm, a valve operating 10 device on said handle, a pulley on the top of said column, a cord connecting said valve operating device with a bell-crank lever one arm of which connects by a link with the operating lever of the valve controlling 15 the passage of steam to the buck, and the other one with said cord; and a counter-weight on said arm for operating said valve operating mechanism in the opposite direction, substantially as set forth.

20 2. In a clothes pressing apparatus, a pedestal, a bracket secured thereon, a steam receiving buck on said bracket, a pipe to convey steam thereto, a valve to control the flow of steam through said pipe, a lever to operate said valve, a bell-crank lever secured on said pedestal, a bar pivoted to one arm of said bell-crank lever and to said valve lever, a bifurcated beam, a pivot adapted to hinge said beam to the upper end of said pedestal, a pulley mounted on said pivot between the arms of said bifurcated beam, a presser-plate secured to the arms of said beam adapted to operate upon said buck, a hand roller pivoted between the ends of the arms of said bifurcated beam, an arm on 35 said hand roller and movable therewith, and a flexible connection extending from said arm over said pulley and downwardly in said pedestal to the other arm of said bell-crank lever whereby, by turning said hand roller said valve may be operated, substantially as set forth.

In testimony whereof I affix my signature.
ARTHUR E. SNOW.
